18 Claims. (Cl. 179—171.5)

The present invention relates to an electrical wave generator and among the objects of the invention is to provide an electron discharge tube oscillator for producing sustained oscillations the amplitude and frequency of which may be controlled in an easy and efficient manner.

Another object of the invention is to provide an electron tube oscillator characterized by extreme frequency and amplitude stability.

A further object is to provide an oscillator for converting a direct current to an alternating current of any desired frequency characterized by a complete isolation between the direct current input and the alternating current output circuits.

A further object is the provision of a vacuum tube oscillator whose frequency may be varied directly by a small change in bias potential applied to an electrode of the oscillator tube.

Still a further object is to provide a vacuum tube oscillator which may be easily and efficiently frequency or amplitude modulated by varying a positive bias potential applied to a non-oscillating electrode of the tube.

Another object is to provide a vacuum tube oscillator the frequency of which may be varied by a small change in direct bias potential applied to a negative electrode of the tube.

A further object is to provide a low frequency oscillator utilizing a minimum of discharge tubes and parts and providing extreme frequency stability and substantially distortionless output.

Still another object is to provide a combination of a radio frequency oscillator and buffer amplifier or frequency multiplier characterized by high operational stability and power output and embodying a single electron discharge tube.

A further object is to provide a radio frequency oscillator capable of providing a wide band frequency modulated signal of high stability and requiring low modulating power compared with frequency modulated oscillators known in the prior art.

Still a further object is to provide an electron tube oscillator embodying the piezo-crystal characterized by extreme frequency and amplitude stability.

Still a further object is to provide an electron tube oscillator whose oscillating electrodes draw no direct current.

Another object is to provide a first detector-oscillator combination for use in superheterodyne radio receivers wherein the oscillating frequency may be directly controlled by a small direct bias potential applied to the oscillator.

The above and further objects and aspects of the invention will become more apparent from the following detailed description taken with reference to the accompanying drawings forming part of this specification and wherein:

5 Figure 1 is a circuit diagram representing a basic oscillator circuit embodying the principles of the invention.

Figure 2 shows a circuit similar to Figure 1 embodying means for controlling the frequency and other characteristics of the oscillator.

Figure 3 is a graph representing frequency as a function of negative grid potential in an oscillator according to Figure 2.

15 Figure 4 is a further graph showing the frequency as a function of the positive voltage applied to the screen grid or accelerating electrode in the oscillator according to Figure 1.

Figure 5 is a graph showing the amplitude of 20 the oscillations as a function of the positive screen or accelerating voltage in an oscillating circuit according to Figures 1 and 2.

Figure 6 shows a modification of the oscillator circuit shown in Figures 1 and 2.

25 Figure 7 is a graph showing the amplitude of the oscillations as a function of the screen grid or accelerating voltage in an oscillator according to Figure 6.

Figures 8 and 9 represent oscillating circuits 30 according to the invention embodying a piezoelectric crystal or an equivalent oscillating device to ensure extreme frequency stability.

Figure 10 shows a modification of an oscillator according to the invention comprising an oscillator system and buffer amplifier embodied in a 35 single discharge tube.

Figure 11 shows a low or beat frequency oscillator constructed in accordance with the principles of the invention.

40 Figure 12 is a complete circuit diagram of a superheterodyne receiver embodying a local oscillator and other features of improvement in accordance with the invention.

Figures 13 and 14 illustrate modifications for 45 employing an oscillator according to the invention in the converter stage of a superheterodyne receiver.

Figures 15 and 16 are diagrams of phase or 50 frequency modulated radio transmitters embodying an oscillator according to the invention.

Like reference numerals identify like parts throughout the different views of the drawings.

Referring more particularly to Figure 1, there is shown a basic radio frequency oscillator constructed in accordance with the principles of the

invention. Item 10 represents an electron discharge tube in the example shown a tetrode comprising a cathode 11, a control grid 12, an accelerating or screen grid 13 and an anode or plate 14. A parallel resonant circuit comprising an inductance 15 and a variable condenser 16 is connected between the grid 12 and cathode 11 and a similar parallel tuned circuit comprising a variable condenser 17 and an inductance 18 is connected between plate 14 and the cathode. Both the grid 12 and the plate 14 which constitute the sole oscillating electrodes of the circuit are maintained at a negative steady potential with respect to the cathode by the provision of suitable biasing potential sources such as batteries 20 and 21 by-passed for radio frequency by condensers 22 and 23, respectively. The accelerating, or screen grid 13 is maintained at a positive steady potential with respect to the cathode by connecting it to the positive pole of a suitable high tension source indicated by the plus sign in the drawings while maintaining this grid at cathode or ground potential for alternating or oscillating currents by the provision of a suitable by-pass condenser 24.

If in a system aforescribed an input signal potential e_1 having a frequency f is impressed between the grid 12 and cathode 11, the electron stream accelerated from the cathode 11 through the grid 12 towards the positive screen or accelerating grid 13 will be directly modulated in accordance with the variations of this potential on the input or control grid 12. Most of the electrons will pass through the meshes of the accelerating grid 13 and form a concentrated space charge or virtual cathode in the region between the accelerating grid and the plate 14 by reason of the decelerating effect of the latter on the electrons. The fluctuations of the density of this virtual cathode or space charge in the rhythm of the variations of the input potential e_1 will cause a corresponding current to flow in the return connection between plate and cathode, or in other words, a so-called space charge coupling will exist between the grid circuit and plate circuit of the tube. This induced current, being a displacement current will be phase shifted 90° with respect to the voltage e_1 that causes it and will be of the same frequency as the input potential e_1 .

Considering now the tuned circuit 17-18 connected between the plate 14 and cathode 11 to be replaced by an ohmic resistance, it is seen that the induced current i_2 in the plate circuit flowing through this resistance will develop a voltage e_2 in phase with the current i_2 and, in view of the property of the space charge coupling, this current being a displacement current will be phase shifted by 90° with respect to the space charge fluctuations, i. e., in turn with respect to the input voltage e_1 . Hence, the voltage e_2 between the plate 14 and cathode will be 90° phase shifted with respect to the voltage e_1 between the grid 12 and cathode. Now, if the ohmic resistance connected between the plate 14 and the cathode is replaced by the parallel tuned circuit 17-18 as shown, having a resonant frequency f_x , a further phase shift of the potential e_2 developed at the plate 14 with respect to e_1 will occur. If f_x is equal to f or the frequency 70 of the input signal e_1 , the impedance of the resonant circuit 17-18 will be a pure ohmic resistance and in this case the voltage e_2 will be phase shifted by 90° with respect to the voltage e_1 as explained in the foregoing. If, on the other 75

hand, f_x is higher or lower than the frequency f of the voltage e_1 an additional phase shift will be produced in either direction due to the properties of the resonant circuit 17-18 and accordingly, the phase shift between e_2 and e_1 will vary above and below the normal 90° phase shift depending on whether f_x is greater or smaller than the frequency f of the voltage e_1 . If f_x is much greater than f or if f_x is much less than f , the voltage e_2 will be in phase or 180° out of phase with respect to the voltage e_1 depending on the sense of departure of f_x from f .

It has been shown above that a variation of the space charge in front of a negative electrode 15 will cause a displacement current to flow through the electrode and its associated circuit resulting in a voltage of the same frequency as the space charge variations being developed across this circuit. Thus, as described in the foregoing, a voltage e_1 impressed between the grid 12 and cathode 11 will result in a voltage e_2 between the plate 14 and cathode, the latter being phase shifted with respect to e_1 by 90° if the circuit 17-18 is tuned to the frequency of the impressed voltage e_1 and varying in either direction from the normal 90° phase shift in proportion to the departure of the resonant frequency of the circuit 17-18 from the frequency of the voltage e_1 . It has been found that the relationship between the grid 12 and plate 14 may be reversed, that is, if an input potential is impressed upon the plate 14 a corresponding potential will be established on the grid 12 by virtue of the space charge coupling in substantially the same manner as described above but with the essential difference that the 90° phase shift in this case will be exactly in the opposite direction from the 90° phase shift obtained in the case when the input voltage is impressed upon grid 12 and the output potential developed on the plate 14. This effect is obviously due to a second space charge set up in the vicinity of the control grid 12 by the electrons after having been repelled and passing the positive grid in inverted sense. 45 From the foregoing it is seen that if a voltage e_2 is developed across the circuit 17-18 as a result of a voltage e_1 impressed between the grid 12 and cathode 11 by the action of the space charge or virtual cathode, a similar effect 50 will be produced in the opposite direction, that is, a current designated as i_3 will be developed in the circuit 15-16 by the effect of the voltage e_2 by virtue of the space charge couplings in both directions between the grid 12 and plate 14. Accordingly, therefore, e_2 will develop a current i_4 in the circuit 15-16 and since this current will be phase shifted by 90° with respect to e_2 in an opposite sense to the 90° phase shift between e_1 and e_2 , provided the circuits 15-16 and 17-18 55 are tuned to the same frequency, the feedback current i_4 will be in phase with the current in the circuit 15-16 thereby tending to augment or maintain the latter. In other words, the feedback voltage e_3 developed by the flow of i_4 through 15-16 will be exactly in phase with the exciting voltage e_1 and tend to sustain the latter in such a manner as to enable the circuit to operate as an oscillator for continuous or sustained oscillations having a frequency determined by the resonant frequency of the circuits 15-16 and 17-18. 60 The starting or initiation of the oscillations is explained as follows: If either of the circuits 15-16 or 17-18 is connected and power supplied

to the accelerating electrode 13, a damped oscillating voltage e_1 will be developed between the grid 12 and cathode 11. This voltage will cause a quadrature voltage of the same frequency to be established between the plate 14 and cathode in the manner described hereinabove. This voltage e_2 will in turn cause a feedback voltage exactly in phase with the voltage e_1 to be developed across the circuit 15-16 tending to sustain the initial damped oscillations. Accordingly, therefore, by a proper design of the damping coefficients or "Q" of the circuits 15-16 and 17-18 and other characteristics of the system continuous or sustained oscillations will be maintained in the oscillatory circuits either of which may be connected to a suitable utilization circuit.

The maximum amplitude of the oscillations will be a function of the direct bias voltage on the negative oscillating electrodes, for if either electrode is driven positive the virtual cathode in front of that electrode will be weakened or destroyed. Hence, the oscillations will be limited by the bias on the negative electrodes 12 and 14, respectively. The bias on these electrodes will also affect the frequency of the oscillations since the spacing of the virtual cathode from the negative electrodes varies the space charge capacity forming a part of the capacitative reactance of the oscillatory circuits. In a like manner, varying the screen potential will also affect the space charge and cause a corresponding frequency variation. The amplitude of the oscillations is further dependent on the Q-value of the resonant or oscillatory circuits. With the Q of the circuits reduced below a critical value, the maintenance of sustained oscillations will cease since the current i_2 will not develop a sufficient voltage e_2 across the tuned impedance and in turn the feedback voltage e_1 in this case will not have sufficient amplitude to sustain the oscillations. It is found that there is also a critical screen or accelerating potential for a particular type of tube below which no virtual cathode will be formed and self-generated oscillations will no longer be obtained. Increasing the accelerating or screen potential above this critical point will increase the amplitude almost linearly provided a suitably by-passed cathode bias resistor is employed whereby current through the latter will increase with increasing screen voltage and hence the negative bias on the oscillating electrodes will increase with an increase in screen voltage as will be further explained with reference to Figures 6 and 7.

Figure 2 shows an oscillator circuit substantially similar to Figure 1 but including means for adjusting the steady grid bias E_1 and the accelerating or screen potential E_{sg} by the provision of suitable voltage dividers 20' and 26, respectively. D. C. microammeters 26 and 27 are shown inserted in the grid and plate circuits for measuring the D. C. grid and plate current drawn by the oscillating electrodes.

Figure 3 is a graph showing the oscillating frequency f as a function of the negative bias E_1 on grid 12 obtained with a circuit shown in Figure 2. As is seen, a straight line is obtained between the values of about -1 volt and -4 volts for a constant screen voltage E_{sg} and a steady negative plate potential E_2 (+105 volts and -2.9 volts for the tube used in the experiments conducted by applicant). Within the straight line portion of the curve a 30 k. c. frequency shift is obtained and accordingly if the normal bias on the grid 12 is about -2.5 volts a deviation ΔE_1

of ± 1.5 volts will afford a frequency shift Δf of ± 15 k. c. This shift will be linear and equal to about 1 k. c. per $\frac{1}{2}$ volt grid bias change. Accordingly, by using an audio voltage of maximum amplitude $\pm 1\frac{1}{2}$ volts either phase or frequency modulation may be obtained from this oscillator. Since the plate bias is held constant the radio frequency output voltage present in the plate circuit will be substantially constant. It is found that no D. C. current is drawn by either oscillating electrode as evidenced by the milliammeters 26 and 27 which remained exactly at zero.

Figure 4 is a graph showing the frequency f of the oscillations as a function of the screen or accelerating voltage E_{sg} , with the bias voltage on the grid 12 (E_1) and on the plate 14 (E_2) being held constant (2.9 volts for the tubes used during the experiments conducted by applicant). This graph also shows a linear relationship between the change in accelerating voltage and the variation in frequency over a substantial operating range.

Figure 5 is a graph showing the peak radio frequency output voltage of the oscillator as measured on a slide back type peak volt meter as a function of the accelerating or positive screen potential E_{sg} . The grid and plate bias potentials E_1 and E_2 were held constant at -2.9 volts. The limited amplitude of the output voltage of approximately .3 volt less than the bias voltage on the oscillating electrodes may be explained by the fact that there must exist a minimum negative potential on the oscillating electrodes at all times to ensure a minimum space charge or virtual cathode.

The graphs according to Figures 4 and 5 show that a direct phase or frequency modulation may be effected in an oscillator of the type proposed by the invention in a most simple and easy manner by modulating the screen voltage in accordance with a suitable modulating potential and by holding the grid and plate bias constant. A phase or frequency modulated oscillation may be obtained having a substantially constant amplitude by operating the screen or accelerating electrode at a point beyond a critical voltage which in the example shown is equal to about 60 volts for the particular tube used in the experiments. Phase or frequency modulation may be effected by varying the D. C. negative bias on one of the oscillating electrodes.

Figure 6 shows an oscillating circuit similar to the preceding diagrams wherein the grid 12 and plate 14 are biased by a common biasing arrangement 28 comprising a resistance by-passed by a condenser inserted in the common cathode return for the grid and plate circuits.

Figure 7 shows a graph representing the peak radio frequency output voltage as a function of the screen potential E_{sg} obtained with a circuit shown in Figure 6. It is found that a change of the screen potential will no longer produce a change in the oscillating frequency that is the frequency will be substantially constant independently of the screen or accelerating potential. This may be explained in the following manner. As the screen potential is increased the screen current will likewise increase, and accordingly, a greater voltage drop will be developed in the cathode bias resistor 28. As more voltage is developed across the latter, the grid 13 and plate 14 will become increasingly negative and accordingly the frequency variations due to changes of the screen potential will be cancelled by the variations due to change in the negative bias poten-

tial on the grid 12 and plate 14. The increase in the screen potential bias will of course cause an increase in amplitude of the oscillations and for this reason, the oscillator according to Figure 6 has a substantially linear amplitude characteristic as a function of the screen potential as shown in Figure 7. The slope of this characteristic depends upon the design and characteristic of the particular tube used. The curves shown were obtained with the standard type tubes 1852 and 6SA7 available on the market and being in wide usage. Thus, the oscillator according to the invention may be utilized to produce an efficient and highly stable amplitude or frequency modulated oscillation for signalling, testing and various other purposes.

As will be evident from the foregoing the present invention discloses a true electron coupled oscillator wherein the oscillations are sustained solely by electron or space charge coupling within a discharge tube. Without this electron or space charge coupling no oscillations could be produced or sustained. The advantages of this type oscillator are manifold as will further appear from the following.

As is well known, the stability of a radio frequency oscillator is directly a function of the Q of the oscillatory circuits in that the higher the Q the greater the stability of the oscillations. Accordingly, therefore, the oscillator proposed by the invention has great advantages over the known oscillators due to the fact that there is no longer any load whatsoever imposed upon the tuned or oscillatory circuits. This is true because the oscillating electrodes draw no direct current whatsoever. In the usual type of oscillator on the other hand, the plate has a certain definite impedance usually on the order of several thousand ohms and the plate current draws an appreciable direct current. This impedance is shunted directly across the tuned circuit of the oscillator. Furthermore, the grid bias in the known oscillators is obtained by means of a grid leak and condenser by virtue of the fact that the grid is driven positive during part of the oscillating cycle and hence will develop a bias voltage due to direct current flowing through the grid leak resistance. Accordingly, the grid likewise has a certain definite impedance at the time during which it is driven positive also causing a dampening effect and consequent reduction of the Q of the oscillatory circuit connected to the grid.

In the oscillator of the type disclosed by the invention, on the other hand, these drawbacks are completely eliminated. Neither of the oscillating electrodes draws any direct current and accordingly since these electrodes are negatively biased and since there is practically no load whatsoever imposed upon the oscillatory circuits the Q of the latter will not be reduced in any manner whatsoever. A further advantage of the oscillator proposed by the invention is the fact that the oscillator tube works more smoothly since the direct current input is completely isolated from the radio frequency circuits, thus further eliminating the need for elaborate by-pass and filter elements to isolate the direct current circuits from the oscillating or alternating current circuits and from the output circuit as is necessary in the standard type of electron tube oscillators. A further advantage of the oscillator proposed by the invention resides in the ease of coupling the output to a utilization circuit. Inasmuch as there is no high direct current po-

tential upon the oscillating electrodes blocking condensers and the like are completely dispensed with. Still a further advantage of the invention is due to the ease of obtaining extremely high output by means of an oscillator-buffer arrangement without in any manner impairing the frequency stability or wave form of the oscillator, that is any type or value of load impedance may be connected in the output circuit without in any way reacting upon and effecting the operation of the oscillator. A further advantage is the fact that the oscillations are developed at the resonant frequency of the tuned tank circuits 15-16 and 17-18, rather than at a frequency slightly different from the resonant frequency as in known oscillators.

A further advantage is the fact that the invention is readily applicable to tubes commercially available and in wide usage at the present time.

Figure 8 shows a modification of the invention utilizing a quartz crystal 30 shunted by a resistance 31 to provide a D. C. return for the grid 12 as an oscillatory element connected between the grid 12 and cathode of the oscillator tube. This circuit has the advantage of extreme frequency stability due to the combined properties of the quartz crystal and the circuit according to the invention. The main advantage of an oscillator of this type is the fact that there is substantially no current flowing through the crystal and the voltage developed across the crystal is only of the order of a few volts. Accordingly, heating of the crystal caused by high radio frequency potential and due to high amplitude mechanical vibration is held at a minimum. By suitably limiting the negative bias on the oscillating electrodes the amplitude of the oscillations may be reduced to a very low value and accordingly the heat generated in the crystal may be held at a minimum. This condition may be easily obtained by reducing the bias resistor in the cathode return lead to the minimum value that will allow stable oscillation. Likewise, the screen potential may be reduced to a very low value and still sustained oscillations may be developed. Resistance 31 may be replaced by a radio frequency choke coil.

Figure 9 shows a modification of Figure 8 wherein the crystal 30 and return resistor 31 are connected between the plate and cathode, the operation and function of this circuit being otherwise identical to that of Figure 8.

Referring to Figure 10, there is shown a further modification of the invention in the form of a combined oscillator-amplifier comprising a single discharge tube. This circuit is substantially similar to the preceding arrangement but differs therefrom in that the plate 14 or second oscillating electrode is replaced by a grid 32 and that an additional output plate 33 is provided biased at a high positive potential with respect to the cathode and having connected to it a suitable output or load impedance. The screen 13 is constructed to serve both as an accelerating electrode for the electron coupled oscillator as well as a screen to prevent reaction from the plate 33 upon the remaining electrodes of the tube. In an arrangement of this type oscillations will be developed by the oscillator section 11-12-13-32 and associate oscillatory circuits 15-16 and 17-18 in substantially the same manner as described previously, which oscillations will modulate the electron stream flowing to the plate 33 and through an output impedance inserted in the plate circuit. This output impedance may be a

resistor, an inductance or a tuned resonant circuit such as a parallel tuned circuit as shown in the drawings comprising a condenser 34 and inductance 35. For small outputs of the order of those required in a superheterodyne receiver the impedance in the plate circuit may be an ohmic resistor in which case the magnitude of the oscillations may be adjusted by varying the value of this resistor or by varying the plate voltage applied to the tube. For higher outputs as required in a transmitter, the load impedance in the plate circuit is advantageously a parallel resonant circuit as shown which latter will offer high impedance to the desired frequency and accordingly, build up a voltage of high magnitude at this frequency. In the latter case the output may be varied by either adjusting the plate voltage or the screen voltage or in any other suitable manner. By tuning the plate impedance to a harmonic of the oscillations any integral multiple of the oscillator frequency may be segregated to obtain output oscillations of desired frequency.

The circuit shown in Figure 10 is extremely useful and advantageous inasmuch as it affords a complete isolation between the output utilization circuit and the oscillator proper and as a variation in the output load will not react in any way upon the oscillator, resulting in extreme operational stability and reliability of this system. In order to prevent direct interaction by stray couplings, the oscillatory circuits 15-16, 17-18, and 34-35 are advantageously shielded by suitable grounded screens 36, 37, 38, respectively, in a manner well understood.

Referring to Figure 11, there is shown a further application of an oscillator proposed by the invention for producing low frequencies utilizing the principle of the well known beat oscillator. There are provided for this purpose a pair of high frequency oscillators at least one of which is constructed in accordance with the present invention and whose outputs are combined to produce a lower beat frequency varying according to the relative frequency adjustment of the high frequency oscillators. In the example illustrated both oscillators are of the type as shown in Figure 10 comprising oscillating tubes 10 and 10' with corresponding elements and associate circuits denoted by simple and primed numerals, respectively. The oscillator 10 includes an additional control grid 40 arranged between the screen 13 and the plate 33 and excited by the output of the oscillator 10' by way of a resistance coupling network 41 of known type. The beat oscillations produced in the plate circuit of the tube 10 by the modulating or mixing action of the electron screen are developed by a suitable network or filter 42 and impressed upon a utilization circuit by way of coupling condenser 44 and coupling resistor 43. By controlling the frequency of either of the oscillators preferably by the aid of a variable bias potential in the manner described and shown for instance in Figure 2, it is possible to obtain a highly stable low frequency output current whose frequency may be varied and accurately adjusted to a desired value.

Referring to Figure 12, there is shown a circuit diagram for a superheterodyne radio receiver embodying an oscillator according to the invention to obtain high stability as well as other features of improvement with a minimum of parts and circuit elements. Radio signals received by an antenna 45 or other input circuit are impressed by way of a tuned radio frequency 75

transformer 46 upon the grid 52 and cathode 48 of a first detector-oscillator or electronic mixer tube 47 comprising further a cathode 48, first oscillating grid 49, a screen grid 50, second oscillating grid 51, suppressor grid 53 internally connected to the cathode 48 and an anode or plate 54. Item 55 is a biasing network in the cathode circuit to provide suitable negative operating bias for the oscillating grids 49 and 51 as well as the signal input grid 52. The screen grid 50 is constructed in such a manner as to act both as an accelerating electrode for the oscillator section as well as an electrostatic screen between the latter and the signal grid 52 on the one hand and between the plate 54 and the remaining electrodes of the tube on the other hand. Oscillatory circuits 56 and 57 are connected to the oscillating grids 49 and 51, respectively, whereby local oscillations will be generated in the manner described and the electron stream passing the signal control grid 52 will be initially modulated in accordance with these oscillations. By the additional control of the electron stream in accordance with the input signal frequency by the action of grid 52 intermediate frequency signals are produced in the plate circuit of the tube which are impressed upon the input of the intermediate frequency amplifier stage 60 by way of the tuned coupling transformer 58. The adjustable elements of the oscillatory circuits 56 and 57 of the input circuit are suitably tracked and ganged as indicated in dotted lines to effect a uni-control in a manner well known to those skilled in the art. The intermediate frequency amplifier 60 in the example shown is of the hexode-diode type comprising a cathode 61, input control grid 62, screen grid 63, further control grid 64, suppressor grid 65 internally connected to the cathode 61 and 40 anode or plate 66. Item 67 is a biasing network in the cathode circuit to provide proper operating bias for the control grids 62 and 64. Grid 64 is connected to ground or cathode through a parallel tuned circuit 68 resonant to the intermediate frequency for the purpose to be described hereafter. The amplified signal current variations at intermediate frequency in the plate circuit are impressed by way of a tuned transformer 69 upon the diode rectifier circuit comprising diode plate 71 and load resistor 70. The demodulated or audio signal voltage developed by the latter is impressed upon the input of the first triode section of a double triode audio amplifier tube 74 by way of blocking condenser 72 and adjustable grid lead resistance 73. The amplified audio output is impressed upon the input of the second triode section of tube 74 by way of coupling condenser 75 and grid leak resistance 76. The output of the second triode section serves to energize a suitable translating device such as a loud speaker 78 connected to the output circuit of tube 74 by way of audio frequency transformer 77.

There are further shown in Figure 12 means 65 to effect an automatic tuning control by readjusting the frequency of the local oscillator section of the mixer tube 47 whenever the intermediate signal frequency departs from the fixed resonant frequency of the intermediate frequency amplifier. For this purpose a tune correcting or discriminating potential is generated in the output of the intermediate frequency amplifier 60 by the action of the tuned circuit 68 in a manner described in U. S. Patent 2,208,091 to I. Zakarias. The tuned circuit 68 being excited

by space charge coupling with the electron stream modulated in accordance with the intermediate frequency signals impressed upon the grid 62 will cause a potential of varying phase to be established upon the grid 64 depending upon the departure of the impressed intermediate frequency from the frequency to which the circuit 68 is resonant. As a result, the plate current will include a direct component varying both in sense and magnitude in proportion to the frequency departure of the intermediate frequency signals from the fixed resonant frequency of the circuit 68. A corresponding discriminating voltage is developed in the plate circuit by means of a net-work comprising series resistance 83 and by-pass condenser 84 as described in the aforementioned patent specification and this voltage is impressed upon the oscillating grid 49 of tube 47. Thus, whenever the intermediate frequency which varies proportionally to the received signal frequency deviates from its assigned value, i. e., in turn from the resonant frequency of the tuned circuit 68, a correcting potential will be applied to the grid 49 in such a manner as to reduce this deviation to a minimum or in other words to effect an automatic frequency or tuning control of the receiver. There is thus provided in a single tube a high gain radio frequency amplifier and a discriminator for correcting frequency of radio frequency input voltage.

There are further shown in Figure 12 means for obtaining automatic volume control comprising a low-pass filter 80-82 suitably connected to the diode circuit to derive a potential varying in accordance with the average carrier amplitude and which is impressed upon the signal input grids 52 and 62 of both the mixer tube 47 and the intermediate frequency amplifier 60 in a manner well understood by those skilled in the art. Thus, the receiver described hereinbefore, in addition to the increased operating stability and other advantages inherent in the new type oscillator proposed by the invention, has the further advantage over the standard receiving systems of enabling an automatic frequency control without requiring any additional tubes such as reactor tubes and other circuit elements.

Referring to Figure 13, there is shown a modification of a superheterodyne circuit embodying a local oscillator according to the invention. According to this embodiment, a separate local oscillator is provided of substantially the same type as shown in Figure 10. The output oscillations are impressed by way of a resistance coupling network 110 of known design upon the oscillating control grid 107 of an electron mixer tube 105 of known type comprising further a signal input grid 106 excited by the incoming signal oscillations. The intermediate frequency signals developed in the plate circuit of the tube are applied to the intermediate frequency amplifier by way of a tuned transformer 103 in the manner well understood.

Referring to Figure 14, there is shown a circuit embodying a modified composite mixer tube suited for use in superheterodyne receivers. This tube 90 includes a tetrode and a hexode section with a common cathode 91. The tetrode section comprises control grid 92, screen or accelerating grid 93 and a plate 94, while the hexode section comprises a control grid 95, the screen grid 96 forming a unit with the screen or accelerating grid of the tetrode section, an injector or signal input grid 97 and a plate 100. The screen grid 96

96 is designed to act both as an accelerator for the electron coupled oscillator associated with the tetrode section and as a normal screen grid surrounding the input signal grid 97. Oscillatory circuits 101-102 are connected to the plate 94 and to the control grid 92, respectively, to generate sustained local oscillations in accordance with the invention. The latter are impressed upon the oscillating grid 95 of the hexode section by directly internally connecting the grid 95 with the grid 92, whereby the electron stream accelerated towards the signal input grid 97 will be initially modulated by the local oscillations to produce intermediate frequency signals in the plate circuit in a manner well understood from the foregoing.

Referring to Figure 15, there is shown an embodiment of the invention in a phase modulated transmitter. The oscillator shown is of substantially the same type as described hereinbefore. There is further provided a microphone circuit comprising microphone 111, a battery 112 and an audio frequency transformer 113 for impressing audio potentials upon the oscillating grid 12 to effect a corresponding frequency modulation of the output oscillations in the plate circuit. The latter are transmitted to an antenna 116 or other transmission circuit by way of resonant coupling circuit comprising a variable condenser 114 shunted by an inductance 115. An arrangement as shown in Figure 15 constitutes a most simple and stable low power phase modulated transmitter suitable for communication over relatively short distances. By the insertion of a suitable audio filter across the microphone, the phase modulation may be changed to frequency modulation.

If higher power output is required such as in frequency modulation broadcasting, a system 40 may be employed as shown in Figure 16. In the latter, the frequency modulated oscillations produced by the oscillator are impressed by way of tuned transformer 117 upon a frequency multiplier to increase the frequency deviation, and 45 from there to a power amplifier 119 preceding the radiation system, in the example shown a pair of dipole antennae 120 and 121. In order to 50 eliminate frequency variations caused in the system a frequency control arrangement of known type may be provided comprising a discriminator 122 adapted to generate a control potential varying proportionately to deviations of the oscillating carrier frequency from its assigned value, 55 said control potential being impressed upon one of the frequency controlling electrodes of the oscillator, in the example shown the electrode 32, in such a manner as to counteract and reduce the frequency deviations from the assigned carrier frequency to a minimum.

For generating ultra-high frequency oscillations, it is found that the electron transit time causes a change in the phase angle from 90° of the induced current generated by the varying space charge with respect to the voltage e_1 . Accordingly, it may be found advisable to slightly detune one of the resonant circuits with respect to the other in order to compensate for this phase shift, and to insure that the feedback voltage e_2 is in exact phase with the voltage e_1 .

From the foregoing it is seen that this invention involves basically the utilization of two virtual cathodes or concentrated electron space charges in front of a pair of decelerating or negatively biased oscillating electrodes arranged with respect to a space current supply or ac-

celerating electrode being the only electrode carrying a steady direct current. As a result thereof, a mutual space charge coupling exists between said oscillating electrodes whereby sustained electrical oscillations will be maintained in the oscillatory circuits connected to the latter. By controlling either space charge by varying the respective decelerating potentials or by controlling the accelerating potential on the supply electrode the frequency of the oscillations may be varied within a substantial range due obviously to a varying distance or position of the respective space charges in front of the oscillating electrodes resulting in a variation of the space charge capacity forming a part of the effective tuning reactance of the system.

It will be evident from the foregoing that the invention is not limited to the specific circuits and arrangements of parts shown and disclosed herein for illustration, but that the underlying inventive principle will be susceptible of numerous modifications and variations coming within the broader scope and spirit of the invention as defined in the appended claims. Accordingly, therefore, the specification and drawings are to be regarded in an illustrative rather than a limiting sense.

I claim:

1. An oscillator comprising an electron discharge device having a cathode and an accelerating electrode, a source of potential connected between said accelerating electrode and said cathode to maintain an electron space current through said device, a pair of decelerating electrodes located at opposite sides of said accelerating electrode, means for applying biasing potentials between said decelerating electrodes and said cathode to develop a concentrated electron space charge adjacent thereto, and resonant impedance means tuned to substantially the same frequency connected between said decelerating electrodes and said cathode.

2. An oscillator comprising an electron discharge tube having a cathode and an accelerating grid electrode, a source of potential connected between said accelerating electrode and said cathode to maintain an electron space current through said tube, a pair of decelerating electrodes located at opposite sides of said accelerating electrode, means for applying biasing potentials between said decelerating electrodes and said cathode to develop a concentrated electron space charge adjacent thereto, and parallel tuned oscillatory circuits resonant to substantially the same frequency and connected between each of said decelerating electrodes and said cathode.

3. An oscillator comprising an electron discharge tube having a cathode and an accelerating grid, a source of potential connected between said accelerating grid and said cathode to maintain an electron space current through said tube, a first decelerating grid electrode located between said cathode and said accelerating grid, a further decelerating electrode located at the side of said accelerating grid opposite from said cathode, means for biasing said decelerating electrodes with respect to said cathode to produce a concentrated electron space charge adjacent thereto, and resonant impedance means tuned to substantially the same frequency connected between each of said decelerating electrodes and said cathode.

4. An oscillator comprising an electron discharge tube having a cathode and an accelerating grid, a source of potential connected between said accelerating grid and said cathode to main-

tain an electron space current through said tube, a first decelerating grid electrode located between said cathode and said accelerating grid, a further decelerating electrode located at the side of said accelerating grid opposite from said cathode, means for biasing said decelerating electrodes with respect to said cathode to produce a concentrated electron space charge adjacent thereto, resonant impedance means tuned to substantially the same frequency connected between each of said decelerating electrodes and said cathode, and means to control the spacing of said electron space charge from said decelerating electrodes for varying the frequency of the oscillations produced.

5. An oscillator comprising an electron discharge tube having a cathode and an accelerating grid, a source of potential connected between said accelerating grid and said cathode to maintain an electron space current through said tube, a first decelerating grid electrode located between said cathode and said accelerating grid, a further decelerating electrode located at the side of said accelerating grid opposite from said cathode, means for biasing said decelerating electrodes with respect to said cathode to produce a concentrated electron space charge adjacent thereto, resonant impedance means tuned to substantially the same frequency connected between each of said decelerating electrodes and said cathode, and means for controlling the potential on said accelerating electrode to vary the frequency of the oscillations produced.

6. An oscillator comprising an electron discharge tube having a cathode and an accelerating grid, a source of potential connected between said accelerating grid and said cathode to maintain an electron space current through said tube, a first decelerating grid electrode located between said cathode and said accelerating grid, a further decelerating electrode located at the side of said accelerating grid opposite from said cathode, means for biasing said decelerating electrodes with respect to said cathode to produce a concentrated electron space charge adjacent thereto, resonant impedance means tuned to substantially the same frequency connected between each of said decelerating electrodes and said cathode, and means for controlling the biasing potential on at least one of said decelerating electrodes to vary the frequency of the oscillations produced.

7. An oscillator comprising an electron discharge tube having a cathode and an accelerating grid, a source of potential connected between said accelerating grid and said cathode to maintain an electron space current through said tube, a first decelerating grid electrode located between said cathode and said accelerating grid, a further decelerating electrode located at the side of said accelerating grid opposite from said cathode, means for biasing said decelerating electrodes with respect to said cathode to produce a concentrated electron space charge adjacent thereto, resonant impedance means tuned to substantially the same frequency connected between each of said decelerating electrodes and said cathode, and means for simultaneously controlling in like sense the steady potentials on said accelerating grid and on at least one of said decelerating electrodes.

8. An oscillator comprising an electron discharge tube having a cathode and an accelerating grid, a source of potential connected between said accelerating grid and said cathode to maintain an electron space current through said tube, a first decelerating grid electrode located between said

cathode and said accelerating grid, a further decelerating electrode located at the side of said accelerating grid opposite from said cathode, means for applying biasing potentials between said decelerating electrodes and said cathode to develop a concentrated electron space charge adjacent thereto, and a pair of parallel tuned circuits resonant to substantially the same frequency each connected between one of said decelerating electrodes and said cathode.

9. An oscillator comprising an electron discharge tube having a cathode and an accelerating grid, a source of potential connected between said accelerating grid and said cathode to maintain an electron space current through said tube, a first decelerating grid electrode located between said cathode and said accelerating grid, a further decelerating electrode located at the side of said accelerating grid opposite from said cathode, means for applying biasing potentials between said decelerating electrodes and said cathode to develop a concentrated electron space charge adjacent thereto, a piezo-electric crystal element connected between one of said decelerating electrodes and said cathode, a high impedance permeable to direct current shunting said crystal, and a parallel tuned circuit resonant to the crystal frequency connected between the other decelerating electrode and said cathode.

10. An oscillator comprising an electron discharge tube having a cathode, an accelerating grid and an anode, sources of potential connected between said accelerating grid and anode and said cathode to maintain an electron space current through said tube, a first decelerating grid located between said cathode and said accelerating grid, a further decelerating grid located between said accelerating grid and said anode, means for applying biasing potentials to said decelerating grids with respect to said cathode to produce a concentrated electron space charge adjacent thereto, resonant impedance means tuned to substantially the same frequency connected between each of said decelerating grids and said cathode, and high frequency load impedance means connected to said anode and cathode.

11. An oscillator comprising an electron discharge tube having a cathode, an accelerating grid and an anode, means for maintaining said accelerating grid and said anode at steady positive potentials with respect to said cathode to maintain an electron space current through said tube, a first decelerating grid located between said cathode and said accelerating grid, a further decelerating grid located between said accelerating grid and said anode, means for applying biasing potentials between said decelerating grids and said cathode to produce a concentrated electron space charge adjacent thereto, resonant impedance means tuned to substantially the same frequency connected between each of said decelerating grids and said cathode, high frequency load impedance means connected between said anode and cathode, and means to substantially prevent capacitative reaction between said anode and said accelerating grid.

12. An oscillator comprising an electron discharge tube having a cathode, an accelerating grid and an anode, means for maintaining said accelerating grid and said anode at steady positive potentials with respect to said cathode to maintain an electron space current through said tube, a first decelerating grid located between said cathode and said accelerating grid, a further de-

celerating grid located between said accelerating grid and said anode, means for applying biasing potentials between said decelerating grids and said cathode to produce a concentrated electron space charge adjacent thereto, resonant impedance means tuned to substantially the same predetermined frequency connected between each of said decelerating electrodes and said cathode, a parallel tuned load circuit also resonant to said predetermined frequency connected between said anode and cathode, and means to substantially prevent capacitative reaction between said anode and said accelerating grid.

13. A high frequency oscillator comprising an electron discharge tube having a cathode, a space current supply electrode and a pair of oscillating electrodes, oscillatory circuits tuned to substantially the same frequency connected between each of said oscillating electrodes and said cathode, a source of potential connected between said supply electrode and said cathode, and means for maintaining said oscillating electrodes at negative potentials with respect to said cathode to produce a concentrated electron space charge adjacent thereto and to maintain sustained self-excited oscillations in said circuits.

14. A high frequency oscillator comprising an electron discharge tube having a cathode, a space current supply electrode and a pair of oscillating electrodes, oscillatory circuits tuned to substantially the same frequency connected between each of said oscillating electrodes and said cathode, a source of direct current potential connected between said supply electrode and said cathode, means for maintaining said oscillating electrodes at negative potentials with respect to said cathode to produce a concentrated electron space charge adjacent thereto to maintain sustained self-excited oscillations in said oscillatory circuits, and means to control the distance of the space charge from at least one of the oscillating electrodes to vary the frequency of the oscillations produced.

15. A frequency modulated oscillator comprising an electron discharge tube having a cathode, a space current supply electrode and a pair of oscillating electrodes, oscillatory circuits tuned to substantially the same frequency connected between each of said oscillating electrodes and said cathode, a source of direct current potential connected between said supply electrode and said cathode, means for maintaining said oscillating electrodes at negative potentials with respect to said cathode to produce a concentrated electron space charge adjacent thereto and to maintain sustained self-excited oscillations in said oscillatory circuits, and means comprising a signal source to control the bias potential of at least one of said oscillating electrodes to vary the frequency of the oscillations produced.

16. An electrical oscillator comprising an electron discharge tube including a cathode and a pair of decelerating electrodes, means for developing a concentrated electron space charge in the vicinity of said decelerating electrodes, and resonant impedance means tuned to substantially the same frequency connected between each said decelerating electrodes and said cathode.

17. An electrical oscillator comprising an electron discharge tube including a cathode, an accelerating electrode and a pair of decelerating electrodes located on either side of said accelerating electrodes, means for developing a concentrated electron space charge in the vicinity of said decelerating electrodes, and resonant impedance means tuned to substantially the same frequency

connected between each of said decelerating electrodes and said cathode.

18. An electrical oscillator comprising an electron discharge tube having a cathode, an accelerating electrode, and a pair of decelerating electrodes, means for developing a concentrated electron space charge in the vicinity of said decelerating electrodes, the coupling effected by the space

charge from the first to the second decelerating electrode being of opposite polarity to the coupling effected by the space charge from the second to the first decelerating electrode, and resonant impedance means tuned to substantially the same frequency connected between each of said decelerating electrodes and said cathode.

HENRY M. BACH.
